UNITED STATES PATENT OFFICE.

FREDERIC SCHAEFER, OF PITTSBURGH, PENNSYLVANIA.

COTTER PIN.

Application filed May 9, 1923. Serial No. 637,706.

To all whom it may concern:

Be it known that I, FREDERIC SCHAEFER, a citizen of the United States, and a resident of Pittsburgh, in the county of Allegheny and State of Pennsylvania, have invented a new and useful Improvement in Cotter Pins, of which the following is a specification.

The invention relates to cotter pins of the general type disclosed in U. S. Patent No. 1,393,139 to Kiesel, and the object thereof is to improve that type of cotter pins to the end that they may not be easily removed from structures in which they are used.

The invention is illustrated in the accompanying drawings of which Figs. 1 and 2 are elevations of one form of cotter pin, the views being taken at right angles to each other; Fig. 3 a transverse sectional view taken on the line III—III, Fig. 2; Fig. 4 a view corresponding to Fig. 1 showing a modification of construction; and Fig. 5 a transverse sectional view taken on the line V—V, Fig. 4.

The cotter pin provided according to this invention includes a pair of resilient arms and a head integrally connecting the arms at one end, the free ends of the arms being provided with outwardly-extending shoulders for retaining the pin in position. The free ends of the arms are, by reason of the resiliency of the material from which the pin is made, urged yieldingly away from each other, and a locking dog is so arranged between the arms that, when the pin is being inserted in an opening, the locking dog does not prevent the free ends of the arms from being sprung toward each other, and that, after the pin has been inserted in an opening, the locking dog may be moved to a position between the free ends of the arms to prevent their being sprung inwardly. While the pin may be variously constructed, it is preferably formed from a single strip of resilient metal, channel-shaped or semi-tubular in cross section, with the concavities of the two arms facing each other and forming an opening extending longitudinally of the pin. The locking dog is arranged in this opening and preferably takes the form of a block of metal slidably borne or supported by one of the arms. Suitable means are provided for holding the locking dog in its alternate positions.

In the embodiment of the invention illustrated in Figs. 1, 2 and 3 the pin is formed from a single strip of channel-shaped metal

and comprises a pair of arms 1 and 2, the upper ends of which are integrally connected to each other by a head 3. The lower ends of the arms are provided with outwardly extending shoulders 4 and 5 which, when the pin is in use, bear against the wall surrounding the end of an opening in which the pin lies, and thus obstruct the removal of the pin. A locking dog 6, in the form of a substantially cylindrical block of metal, is arranged between the arms 1 and 2 and is slidably connected to arm 2 by means of a headed pin or rivet 7, the shank of which lies in a slot 8 formed in arm 2 and extending longitudinally thereof. That the presence of the head of pin 7 may not interfere with the insertion and removal of the pin, the portion of arm 2 adjacent the slot 8 is depressed as indicated at 9.

While a pin is being placed in an opening, the locking dog is held in the uppermost position indicated in Fig. 1, preferably by a pair of detents 10 and 11 pressed inwardly from the body of arm 2. After the pin has been inserted in an opening, locking dog 6 is moved to the lower position indicated in Fig. 1, and for this purpose the central portion of head 3 is preferably provided with an opening 12 through which a suitable tool may be inserted to drive the locking dog past detent 11 to locking position, that is to say to its position between the free ends of the arms. The locking dog is held in this position by and between overhanging lips 13 at the ends of the arms and detent 11. In such position of the locking dog the free ends of the arms may not be sprung inwardly to remove the pin. However, this may be done by placing a tool between the free ends of the arms and driving the locking dog back wardly to its uppermost position.

In the embodiment of the invention illustrated in Figs. 4 and 5 arms 21 and 22 and head 23 of the pin are of the same general form and construction as in the pin previously explained. For slidably supporting a locking dog 26, the edges of arm 22 are provided with inwardly turned flanges 15 which lie in grooves 16 formed in the sides of the locking dog. The locking dog may be held in its upward position between detents 27 and 28 which correspond with the detent 10 and 11 of Fig. 1, and may be held in its lowermost position by and between detent 28 and overhanging lips at the ends of the arms. In this form of construc-

tion the locking dog is moved to and from its alternate positions in the same manner as explained with reference to the pin of Figs. 1 and 2.

5 The improved cotter pin may be used to connect lids to journal boxes, as shown in said Kiesel patent, as well as for any other specific purpose. When a pin has been placed in position and its locking dog moved 10 to prevent the free ends of the arms from being sprung inwardly, the pin may not be accidentally removed. Furthermore, it cannot be removed by anyone who does not have at hand the necessary tools to move the locking dog from between the ends of the arms, and accordingly, when used for fastening 15 lids to journal boxes, it has the advantage of preventing or deterring unauthorized workmen from taking a lid from one car and 20 putting it on another.

According to the provisions of the patent statute, I have explained the principle and operation of my invention in connection with two embodiments thereof. However, I 25 desire to have it understood that, within the scope of the appended claims, the invention may be practiced by other forms of constructions than those particularly shown and described.

30 I claim as my invention:

1. A cotter pin comprising a pair of resilient arms and a head integrally connecting the arms at one end, the free ends of the arms being urged yieldingly away from 35 each other and being provided with outwardly-extending pin-retaining shoulders, a locking dog arranged between said arms and movably borne by one of them, and means for retaining the locking dog in alternate 40 positions of permitting the free ends of the arms to be and preventing them from being sprung inwardly.

2. A cotter pin comprising a pair of resilient arms and a head integrally connect-

ing the arms at one end, the free ends of the arms being urged yieldingly away from each other and being provided with outwardly-extending pin-retaining shoulders, a locking dog arranged between said arms and slidably supported by one of them, and detents on said dog-supporting arm for retaining the locking dog in alternate positions of permitting the free ends of the arms to be and preventing them from being sprung inwardly.

3. A cotter pin comprising a pair of resilient arms and a head integrally connecting the arms at one end, the free ends of the arms being urged yieldingly away from each other and being provided with outwardly-extending pin-retaining shoulders, said arms being substantially semi-tubular in cross-section and forming between them an opening 60 extending longitudinally of the pin, a locking dog arranged in said opening and slidably supported by one of said arms, and means for retaining the locking dog in alternate positions of permitting the free ends of the arms to be and preventing them from being sprung inwardly.

4. A cotter pin formed of an integral strip of resilient metal semi-tubular in cross-section and comprising a pair of arms and a head at one end of them, a locking dog arranged between said arms and slidably supported by one of them, and detents on said dog-supporting arm for retaining the locking dog in alternate positions of permitting the ends of the arms to be and preventing them from being sprung inwardly, the central portion of said head being provided with an opening for inserting a tool to move the locking dog to locking position.

In testimony whereof, I sign my name:

FREDERIC SCHAEFER.

Witness:

EDWIN O. JOHNS.
